UNITED STATES PATENT OFFICE.

CHARLES C. LOCKSTAEDT, OF CHICAGO, ILLINOIS.

REFRIGERATOR.

SPECIFICATION forming part of Letters Patent No.

Application filed December 18, 1891. Serial No.

To all whom it may concern:

Be it known that I, CHARLES C. LOCKSTAEDT, a subject of the Emperor of Germany, residing at Chicago, in the county of Cook and State of Illinois, have invented certain new and useful Improvements in Refrigerators; and I do hereby declare the following to be a full, clear, and exact description of the invention, such as will enable others skilled in the art to which it appertains to make and use the same.

This invention relates to a novel construction in refrigerators, the objects being to provide a refrigerator combining simplicity of construction with efficiency of refrigerating results.

The invention consists in the features of construction hereinafter fully described and specifically claimed.

In the accompanying drawings illustrating my invention, Figure 1 is a perspective view of a refrigerator constructed in accordance with my invention. Fig. 2 is a vertical section on the line 2—2 of Fig. 3. Fig. 3 is a vertical section on the line 3—3 of Fig. 2. Fig. 4 is a detail sectional view of the ice-pan.

The refrigerator box or chest shown in said drawings, broadly considered, is of ordinary construction and shape, having an ice-chest 1 extending down into the box at about the middle thereof, and open at the top. A door 2 hinged to the top of the box closes the said ice-chest as shown. A series of holes or openings 3 are made along the upper portion of the ice-chest for the passage of cold air from said ice-chest to the refrigerator box. Two doors 4 are arranged to close the openings in the front wall of the refrigerator box.

In accordance with the principle comprised by my invention the top, bottom and side walls of the refrigerator box, and the doors 2 and 4, consist of an outer layer 5 conveniently of wood, and an inner layer 6, of sheet metal. Between these two layers 5 and 6 is a filling 7 of bibulous material, that is at the same time a poor conductor of heat. The inner layer 6 is punctured at intervals as shown at 8 so that the bibulous material 7 can absorb the moisture in the refrigerator box. A series of perforations 9 are made in the outer wall of the refrigerator whereby the chamber between the outer and inner walls can communicate with the outside air, and I

find it in the such material that in inventions 9 of the perforations 9 for the be coll of the evapo to the openings 9 of the refrige

able to arrange said openings 9 all of the refrigerator just over occupied by the bibulous ma- 55 will be understood, of course, dance with the principle of my contemplated making the perfor- 60 side or top walls of the refrigerator convenient to arrange the 60 8 in the inner layer 6 in the up- only as shown in Figs. 1 and 3, in that such moisture as might by the porous lining between the refrigerator close to the bottom 65 70 generator would not be likely to wing to distance from such point of the refrigerator where the open- 75 ade in the outer wall of the re- 70

course be understood that various a bibulous nature could be em- 75 it is found that plaster of paris is a good non-conductor and bibulous is obvious that the refrigerator provided with suitable grates and on which articles can be placed. 75 The refrigerator is provided at the bottom 80 with an outlet pipe 10 that passes through the front wall of the refrigerator and 80 11 with a faucet 11 by means of which water may be drawn off. Within 85 an ice-pan 12 is located having means of which it is supported upon the bottom of the ice chest. The ice is 85 placed in the bottom of which is a filter so that the water from the 90 ice will be filtered and can be drawn off from the ice-chest by faucet 11.

The ice-pan 12 preferably consists of a perforated 90 to said ice-pan, a layer 15 of felt 90 bibulous material upon said perforated 90 16, a layer of crushed granite 16 or 95 material upon said felt layer 15, 95 felt layer 17 upon said crushed 95 18, and a perforated plate 18 upon 100 layer 17. The grate 19 for the ice is 100 provided with handles 20 by 100 which it can be lifted from the ice- 100 cleansing or otherwise. It will be understood that filters of other con- 100 struction could be employed but the construction shown is found preferable.

I claim as my invention—

1. A refrigerator having outer and inner walls, an interposed layer of bibulous material, openings or perforations in the inner side walls, and openings or perforations in the outer wall, whereby moisture absorbed by said bibulous layer through openings or perforations in the inner side walls can evaporate through said openings or perforations in the outer wall, substantially as described.
2. A refrigerator having outer and inner walls, an interposed layer of bibulous material, openings or perforations in the upper portion only of the inner side walls, and openings or perforations in the outer wall, whereby moisture absorbed by said bibulous layer through openings or perforations in the inner side walls can evaporate through said openings or perforations in the outer wall, substantially as described.
3. A refrigerator having outer and inner walls, an interposed layer of bibulous material, openings or perforations in the inner side walls, and openings or perforations in the outer top wall, whereby moisture ab-

sorbed by said bibulous layer through openings or perforations in the inner side walls can evaporate through said openings or perforations in the outer wall, substantially as described.

4. A refrigerator having outer and inner walls, an interposed layer of plaster of paris, openings or perforations in the inner side walls, and openings or perforations in the outer wall, whereby moisture absorbed by said layer of plaster of paris through the openings in the inner side walls can evaporate through said openings or perforations in the outer wall, substantially as described.

5. A refrigerator having an ice-chest, an outlet pipe communicating therewith, a removable ice-pan located within said ice-chest, and a filter located in the bottom of said ice-pan.

In testimony whereof I affix my signature in presence of two witnesses.

CHARLES C. LOCKSTAEDT,
